UNITED STATES PATENT OFFICE.

ELIZABETH LENGYEL, OF CLEVELAND, OHIO.

DESIGN FOR A PORTIÈRE.

Application filed January 4, 1927. Serial No. 20,269. Term of patent 7 years.

To all whom it may concern:

Be it known that I, ELIZABETH LENGYEL, a citizen of Hungary, residing at Cleveland, in the county of Cuyahoga and State of Ohio, have invented a new, original, and ornamental Design for Portière, of which the following is a specification, reference being had to the accompanying drawing, forming part thereof.

The figure is a plan view of a portière, being shown in continuous sections to more clearly illustrate the same.

I claim:—

The ornamental design of a portière as shown.

ELIZABETH LENGYEL.
